UNITED STATES PATENT OFFICE.

JAMES F. GORDON, OF LOWELL, MASSACHUSETTS, ASSIGNOR OF ONE-HALF
TO ARTHUR A. BRIGHAM, OF WESTON, MASSACHUSETTS.

WINDING-MACHINE.

SPECIFICATION forming part of Letters Patent No. 664,474, dated December 25, 1900.

Application filed December 18, 1899. Serial No. 740,623. (No model.)

To all whom it may concern:

Be it known that I, JAMES F. GORDON, a citizen of the United States, and a resident of Lowell, in the county of Middlesex and State 5 of Massachusetts, have invented certain new and useful Improvements in Winding-Machines, of which the following is a specification.

My invention relates to winding-machines 10 of that variety which are adapted to wind filaments, thread, cordage, wire, and similar forms of material into balls or cylindrical or tapering cops upon quills, tubes, or bobbins without heads, the layers of material being 15 wound into alternate right and left hand spirals from end to end of the cop.

In machines heretofore constructed for the purpose of winding yarns of different sizes—as, for instance, in the machine shown in 20 United States patent to Wardwell, No. 480,157, dated August 2, 1892—an increment or decrement of motion is given to the winding-spindle at each end of the traverse of the guide in order that the turns of the thread, 25 yarn, or other material at the ends of the cop may not be so superimposed in the different layers wound on the spindle as to give the cop an angular appearance and prevent the formation of a solid cylindrical cop combining the greatest amount of material in the 30 smallest space. This is accomplished in the machine described in said patent by a pawl-and-ratchet contrivance and in other cases by frictional devices, as described in another 35 United States patent to Wardwell, No. 506,959, dated October 17, 1893. These devices are apt to get out of order and are unreliable in their action, the pawl being liable to miss or gain a tooth on its ratchet, owing to the great 40 speed at which the spindle is run, and the contacting surfaces of the frictional devices are apt to slip on each other and to require frequent adjustment. I obviate these objections by a peculiar combination and arrangement 45 of change-gears to connect the cam-shaft (which causes the traverse of the guide) and the spindle-shaft, so that both are driven positively with each other and their relative speeds cannot be accidentally changed. I am 50 enabled by changing the connecting-gears to vary the speed of the rotation of the spindle

relatively to the speed of the traverse of the guide and to secure any desired relation between said speeds.

In a winding-machine adapted for the winding of yarn, thread, or similar material of the size of No. 3 three ply (equal to No. 1 single ply) on a quill or tube in the spiral manner above indicated, assuming that the quill or tube is two and a half inches in length, I have 55 found by experience that the yarn should be laid on the quill at such an angle as to traverse from end to end of the quill and back again in four and twenty-five twenty-sixths revolutions of the spindle. Now in the case 60 assumed if the spindle or bobbin-holder were geared directly to the cam-shaft the gear on the spindle-shaft would need to have twenty-six teeth, or one and two twenty-fourths inches in pitch diameter, and the gear 65 on the cam-shaft would need to have five times as many teeth less one—that is, one hundred and twenty-nine teeth—or a pitch diameter of five and nine twenty-fourths inches, and if a twenty-four pitch diametrical 70 tooth (which is as fine a tooth as could well be used to get the required strength) were used the centers of the shafts would be three and eleven forty-eighths inches apart. Now 75 to change such a machine to adapt it to wind a No. 50 three-ply (equal to a No. 16 two-thirds one ply) yarn or thread would require the substitution on the spindle-shaft of an eighty-toothed gear having a pitch diameter of three and eight twenty-fourths inches 80 and on the cam-shaft of a gear of five times eighty teeth less one, or three hundred and ninety-nine teeth, and would require that the centers of the shafts should be nine and forty-seven forty-eighths inches apart. It 85 will be seen that the two gears in the first instance would occupy a width of space of six and twenty-two forty-eighths inches and in the latter case of nineteen and forty-six forty-eighths inches. The distance apart of 90 the two shafts cannot be changed without readjusting the position of the guide and other parts, which would be impracticable. The only way to avoid the moving apart of the 95 shafts would be to place them at the greatest distance apart ever likely to be required and to bridge over the space between the gears 100

by an even number of intermediate gears—even, because an odd number of intermediate gears would reverse the motion of the driven shaft. If twice as long a quill—that is, a quill 5 five inches long—were to be used, the yarn being the same, the spindle would need to be revolved twice as fast relatively to the speed of the cam-shaft to lay the yarn at the same angle on the quill—that is, the twenty-six-toothed gear on the spindle of the case first supposed remaining the same the gear on the cam-shaft would need to have ten times twenty-six teeth less one, or two hundred and fifty-nine teeth, or a pitch diameter of ten and 15 nineteen twenty-fourths inches, and in like manner if the spindle-shaft gear has eighty teeth and the quill is five inches long the cam-shaft gear would require ten times eighty teeth less one, or seven hundred and 20 ninety-nine teeth, and a pitch diameter of thirty-three and seven twenty-fourths inches. It will be understood that the cam must be changed to vary the length of the traverse. It will also be understood that with the spindle-shaft and the cam-shaft connected by direct gearing two or three different sizes of coarse yarn or thread might be wound without a change of gears, and the same is true to a greater extent of the finer numbers of 30 yarn or thread—that is, the gears which are suitable for a given number of yarn will serve for the next finer numbers; but the finer numbers will in that case be more loosely wound and the maximum amount of yarn will not be 35 wound on the quill or tube; but where the difference in size or number of yarn is considerable the gears must be changed in order to lay the yarns closely side by side without crowding—that is, fine yarn requires a greater number of teeth and coarse yarn a less number of teeth on the spindle-shaft. With too few teeth in the gears the yarn of a given number will be loosely wound and with too many teeth the winds will crowd upon and 45 overlie the other winds of the same layer. The finer number (50 three ply) mentioned above is a medium-sized yarn. Now in winding very fine yarn requiring a gear on the spindle-shaft with a large number of teeth 50 the number of teeth on the cam-shaft would be something enormous and the diameter of the last-named gear would be out of all proportion to the size of the frame of the machine and to the cost of construction in other respects. It is evident that in the case assumed the number of teeth in the driving-gear must be one less than the number of teeth on the spindle-shaft gear multiplied by the number of revolutions of the spindle to 60 one traverse of the guide—that is to say, this ratio must be preserved, although, of course, the number of teeth in both gears may be multiplied by the same number, without any useful effect, however, as the gears if the 65 number of teeth were doubled would be merely twice as large. If a train of gears were used to connect the cam-shaft and spin-

idle-shaft, the gears of the train could not be so compounded as to give the desired result, because the intermediate gears would need 70 to make a greater number of revolutions than the cam-shaft and the number of teeth in the gear which directly drives the spindle-gear should be a multiple of the number of teeth in said spindle-gear less one, and as said driving-gear makes more revolutions than the cam-shaft the spindle will lose or gain an amount as much greater than is required as 75 the speed of the intermediate gears exceeds that of the cam-shaft. For instance, if the intermediate gear makes two revolutions while the cam-shaft makes one revolution the loss or gain will be doubled.

My invention also embraces a stop-motion device which stops the spindle and guide 85 when the cop or the yarn breaks, an automatic tension device, and means of stopping simultaneously the motion of the spindle and guide without stopping the main shaft.

Said invention consists in the devices and 90 combinations hereinafter described and claimed.

In the accompanying drawings, on three sheets, Figure 1 is a left-side elevation of a winding-machine embodying my invention; 95 Fig. 2, an enlarged side elevation of the tension device, partly in central vertical longitudinal section; Fig. 3, a vertical longitudinal section on the line 3 3 in Fig. 4; Fig. 4, a front elevation of said machine; Fig. 5, a vertical transverse section on the line 5 5 in Fig. 1; Fig. 6, a front elevation of the latch of the clutch-locking mechanism and its connections, partly in section; Fig. 7, a plan of the parts shown in Fig. 6, together with the 105 shipping-lever; Fig. 8, a right-end view of the latch, the latch-releasing slide, and a part of the drop-wire.

In the accompanying drawings, A represents a frame of any suitable construction, 110 which supports the moving parts of the machine.

B is the main shaft or cam-shaft, which may be driven continuously at a uniform speed in any usual manner. A heart-grooved cam C 115 is loose to rotate on the shaft B, but is prevented from moving endwise on said shaft by any usual means. From the cam C projects one or more pins c, adapted to be engaged by another pin or other pins c', which project 120 from the adjacent face of a collar C', which surrounds the shaft B and is rotary therewith, but is free to slide longitudinally thereon, said shaft and collar being connected by a spline or feather c² or otherwise in any well-known manner. When the pins on the collar C' and the cam C are in engagement, said cam revolves with the shaft B and gives a reciprocating endwise movement to a guide-rod d, provided with a cross-head d', rigidly attached thereto and having a stud d², which laterally fills the heart-shaped groove c². The upper part of the cross-head d' slides on a bearing-rod d³, arranged parallel with the 130

guide-rod d and supported in brackets a^1 on the frame A. The guide-rod d is further limited to a longitudinal motion by bearings in a bracket a^2 on the frame A and in the front a^3 of said frame. In front of the frame (at the left in Fig. 3) a guide D of usual construction is secured to the guide-rod d , said guide being preferably a plate or strip having in its free end a notch d^4 , Fig. 1, to receive the thread, yarn, or wire being wound. A gear B' is fast on the shaft B and engages a pinion e, the latter engaging a gear e', fast on an intermediate shaft E in the drawings, Fig. 5, represented as a hollow shaft or sleeve, which turns freely on the spindle-shaft F and has a definite number of complete revolutions to each revolution of the main shaft or cam-shaft B or, in other words, to each complete traverse of the guide D. Another gear B², fast on the shaft B, engages a pinion f, which engages a gear f', fast on the hub f² of the disk f³, said disk turning freely on the intermediate shaft E. Two gears e² f⁴ turn with the intermediate shaft E and spindle-shaft F, respectively, one of said gears having a slightly-greater number of teeth than the other. In the drawings, Fig. 1, the gear e² is represented as having one tooth less than the gear f⁴, the numbers of their teeth, respectively, being represented as twenty-five and twenty-six. The gears e² f⁴ are concentric and of the same outside diameter, one or both of said gears being slightly out of the regular proportion to make their diameters equal. An intermediate gear f⁵ turns loosely on a stud f¹⁰, which projects from the outer face of the disk f³ and engages both of said gears e² f⁴, so that the gear f⁴ must revolve when the gear e² is revolved with the shaft E, the gear f⁴, having the greatest number of teeth, at each revolution of the other gear e² falling short of a complete revolution by the angular space measured by the number of teeth which it has in excess of said other gear e². The stud f¹⁰ is adjustable in the radial slot f¹¹ of the disk f³ to enable the gears e² f⁴ to be replaced by others having a larger or smaller diameter. Relatively to each other the gear e² is the driving-gear and the gear f⁴ the driven gear.

From the foregoing description it is evident that if the disk f³ and the shaft E revolve at the same rate of speed the intermediate gear f⁵ will not turn on its center, but will merely lock the two gears e² f⁴ to each other. It will be seen also that if the number of revolutions of the disk f³ is one less than that of the shaft E to a complete revolution of the main shaft B the spindle-shaft F will lose (the gears e² f⁴ having the number of teeth above stated) one twenty-sixth of a revolution in every revolution of the main shaft, or, in other words, in every complete traverse of the guide D; also, that if the relative speeds of the shaft E and the disk f³ be reversed the spindle would make a corresponding gain in each traverse

of the guide; also, that maintaining the same speeds of the shaft E and disk f³ and changing the place of the gears e² f⁴ with each other the result would be reversed—that is, the loss 70 of the spindle-shaft would become a gain.

Motion is communicated from the spindle-shaft F to the bobbin-holder or spindle F' by miter-gears f⁶ f⁷, said spindle being arranged parallel with the rod d and line of traverse of 75 the guide D and at right angles to the main shaft B. The spindle F' is supported in a bearing-sleeve a⁴ in the front end a³ of the frame A and is provided with any usual means of retaining a tube, quill, or bobbin 80 F² thereon, as a toothed annular shoulder f⁸, between which and a nut f⁹, turning in the front end of said spindle, said tube, quill, or bobbin is held. The miter-gear f⁶ is loose on the spindle-shaft, but is caused to 85 rotate with a collar G, similar to the collar C' above described as carried on the main shaft, said collar G having one or more pins g, adapted to enter one or more holes f¹² in said miter-gear. 90

Each of the collars C' and G is provided with a circumferential groove c⁴ g' to receive the free end of one arm of a lever, represented as a rock-shaft H, provided with oppositely-extending arms h h', so that turning said shaft 95 will throw both of said collars into or out of clutch with their respective counterparts. A spring, represented as a spiral spring h², surrounding the shaft H and attached at one end to said shaft and at the other to the frame 100 tends to rotate said shaft H in a direction to open said clutches. The rock-shaft is normally prevented from turning by a latch I, pivoted on the front of the frame A and having a notch i, which drops down over a pin 105 h³, projecting from a third arm h⁴, with which said lever H is provided and which serves as a handle to rock the shaft H into a position to couple the cam C to the main shaft and the miter-gear f⁶ to the spindle-shaft, and thus 110 to set the spindle F' and guide D in motion when the main shaft is running. When the free end (the right end in Fig. 4) of the latch I is raised, the spindle F' and guide D are allowed to come to rest. 115

A tension cam-slide J is guided vertically by a tension-stud j and by a guide-screw j', supported on the front a³ of the frame A, said stud and screw passing through a longitudinal slot j² in said cam-slide. 120

On the tension-stud j are arranged, Figs. 1, 2, 4, 6, and 7, a spring-chamber j³ or hollow cylinder having a closed end j⁴, through which said stud passes; a spring j⁵, surrounding said stud within said chamber j³; a collar j⁶, which enters the outer open end of said chamber j³; a pair of dished tension-washers j⁷ j⁸, with their convex surfaces next each other; another collar j⁹, and a nut j¹⁰, which turns on the screw-threaded outer end portion of said stud j to 125 compress said spring j⁵ to the desired amount. The thread or other material to be wound

passes between the tension-washers through the notch d^4 of the guide D to the tube or bobbin F².

The upward movement of the slide J is limited by a nut j^{11} , turning on the upper end portion of a screw-threaded rod j^{12} , said rod below said nut passing loosely through an ear j^{13} on the back of said slide and the lower end of said rod being hooked through or otherwise secured to said latch, near the outer end of the same, as shown in Figs. 6 and 7. Evidently when the slide J is raised sufficiently it will lift the nut j^{11} , rod j^{12} , and latch I and release the rock-shaft H and allow the clutches to be opened, as above described. The slide J is raised by a bent lever K, one arm k of which reaches under a projection j^{14} from said slide or otherwise engages said slide and the other arm k' of which carries an antifriction-roll k², which rests upon the surface of the cop L or mass of material already wound upon the quill or bobbin. The outward pressure of the growing cop L upon the roll k² through the lever K raises the tension cam-slide J, and the nut j^{11} may be so adjusted that a cop of any predetermined diameter will lift the latch I and allow the clutches to be opened.

It is generally desirable to diminish the tension on the yarn or thread as the cop grows larger because of the increased speed with which said yarn or thread is drawn between the tension-washers, or, perhaps, it might be said to equalize the tension at all times by lessening the pressure of the said washers upon the yarn or thread as the speed of the thread increases. To this end I use a variable incline or piece J', pivoted at its lower end to the front of the slide J and slotted at j^{15} to receive the stud j and resting against the rear end of the spring-chamber j^3 , the pressure of which tends to throw said incline J' backward against the body of the slide. The incline J' is, however, thrown out to the desired angle with said slide J by a screw j^{16} , which turns in a threaded hole in the upper end of said incline J' against said slide J, said screw j^{16} being prevented from accidental turning by a check-nut j^{17} in an obvious manner. It is evident that as the slide J rises the thin edge of the wedge formed by said slide J and the incline J' rises and allows the spring j^5 to expand and the tension-washers j^7 , j^8 to separate.

When the filled tube or bobbin is removed from the bobbin-holder or spindle F², the lever K and slide J are returned to position by the weight of said slide, which may be assisted by the contraction of a spring j^{18} , stretched between said slide and a part of the frame.

To stop the spindle F² and guide D when the yarn breaks, a drop-wire M, having at the outer end a hook m and at the other end m' being pivoted to the latch-lifter N, is used. The lifter N slides in a cap n, secured on the frame at right angles to the latch I, and is provided with an incline n', which when said lifter N is drawn forward raises said latch and

releases the lever H, with the result hereinbefore stated. A stop projection n² on the side of the latch-lifter N, which strikes against the cap n, prevents said latch-lifter from being drawn too far back by a spring n³, which is stretched between said projection and the rear part of said cap to restore said lifter to position. The free or hooked end m of the drop-wire is supported by the tension of the portion of the yarn or thread stretched between the tension-washers and the notch d^4 of the guide D; but when said yarn or thread breaks or becomes too slack (as might happen if the yarn or thread got out from between the tension-washers) said hooked end is caught by the guide D, which draws the lifter forward and raises the latch.

I claim as my invention—

1. The combination of a spindle-shaft, a guide, a main shaft, mechanism connecting said main shaft and guide, to cause the traverse of said guide, an intermediate shaft mechanism connecting said intermediate shaft and said main shaft and adapted to rotate said intermediate shaft a definite number of complete revolutions at one complete traverse of the guide, a driving-gear fast on said intermediate shaft, a gear fast on said spindle-shaft and having a different number of teeth from said driving-gear, and an intermediate gear engaging both of said named gears and mounted to have an orbital movement around the common center of said gears and to rotate freely on its own center and means for causing said orbital movement at a different angular speed from that of said driving-gear.

2. The combination of the cam-shaft, the guide, a cam to cause the same to traverse, the spindle and means of rotating the same, and means of stopping said traversing means and said spindle-rotating means without stopping said cam-shaft.

3. The combination of a spindle or bobbin-holder, means of rotating the same, a guide, tension-surfaces, means of pressing said surfaces together with a yielding pressure, a wedge to vary such pressure, and a lever controlling said wedge and operated by the increase of a cop on said spindle.

4. The combination of a spindle or bobbin-holder, means of rotating the same, a guide, tension-surfaces, means of pressing said surfaces together with a yielding pressure, a wedge to vary such pressure, a lever controlling said wedge and operated by the increase of a cop on said spindle, and an antifriction-roll carried by said lever and resting on said cop.

5. The combination of a frame, a spindle, means of rotating the same, a tension device, adapted to exert a yielding pressure upon the material being wound upon said spindle, a wedge, to vary such pressure, means of varying the angle between the operative faces of said wedge, a lever, engaging said wedge and resting upon a cop on said spindle and oper-

ated by the enlargement of said cop to move said wedge to diminish the pressure of said tension device.

6. The combination of a frame, a tension-
5 stud, tension-pieces on said stud, a spring to crowd said tension-pieces together, a slide movable between said frame and said spring, an incline, pivoted to said slide, means of varying the angle of said incline to said slide, 10 the spindle, means of rotating the same, a lever, engaging said slide and adapted to rest upon the cop on said spindle and to be operated by the increasing size of said cop to raise said slide and diminish the tension of said 15 spring.

7. The combination of a rotating shaft, the spindle, a clutch device, connecting said shaft and spindle, means normally operating to open said clutch, a latch, to prevent the opening 20 of said clutch, a slide, connected to said latch, and a lever, engaging said slide and resting upon a cop being wound on said spindle, to move said slide and to open said latch when

said cop has attained a predetermined diameter.

8. The combination of a main shaft, a cam, loose thereon and forming one counterpart of a clutch, another clutch counterpart, rotary with said shaft and laterally movable thereon, a lever, to open and close said clutch, a spring, 30 to move said lever to open said clutch, a latch, to prevent the clutch-opening movement of said lever, a spindle, a reciprocating guide, operated by said cam, a latch-lifter and a drop, carried by said lifter and normally held 35 out of engagement with said guide by the tension of the material being wound on said spindle, but engaged by said guide to operate said lifter upon the breaking or slackening of said material.

In testimony whereof I have affixed my signature in presence of two witnesses.

JAMES F. GORDON.
